UNITED STATES PATENT OFFICE

118,599

DESIGN FOR A COMBINED VEHICLE SPRING AND SUPPORT THEREFOR

George A. Mercer, Jr., Savannah, Ga.

Application October 12, 1937, Serial No. 72,136

Term of patent 7 years

To all whom it may concern:

Be it known that I, George A. Mercer, Jr., a citizen of the United States, residing at Savannah, in the county of Chatham and State of Georgia, have invented a new, original, and ornamental Design for a Combined Vehicle Spring and Support Therefor, of which the following is a specification, reference being had to the accompanying drawing, forming part thereof.

The figure is a perspective view of a combined vehicle spring and support therefor showing my new design.

The characteristic feature of my design resides in the combination with the spring elements, of the box-like spring hangers or supports at the ends of the springs, into which the ends of the springs extend and are concealed.

I claim:

The ornamental design for a combined vehicle spring and support therefor, as shown and described.

GEORGE A. MERCER, JR.
